CLAIM

I claim the ornamental design for a workout bar, as shown and described.

DESCRIPTION

FIG. 1 is a perspective view of a workout bar of the present application;

FIG. 2 is a front elevational view of the workout bar, wherein the rear elevational view is a mirror image thereof;

FIG. 3 is a right side view of the workout bar, wherein the left side view is a mirror image thereof.

1 Claim, 1 Drawing Sheet(56)
